(57) **CLAIM**

The ornamental design for an open communicator mailer, as shown and described.

DESCRIPTION

FIG. 1 is a front elevational view of an open communicator mailer showing our new design in an opened condition; FIG. 2 is a rear elevational view thereof; FIG. 3 is a front elevational view in a folded condition; FIG. 4 is a rear elevational view thereof; FIG. 5 is a front perspective view in a partially opened condition; and, FIG. 6 is a rear elevational view thereof.

The indicia depicted by means of broken lines in FIGS. 1, 3, and 5 is shown for illustrative purposes only and forms no part of the claimed design.
